UNITED STATES PATENT OFFICE.

NATHAN SPARER, OF SOMERVILLE, AND MAX HALPERSON, OF BOSTON, MASSACHUSETTS.

BUTTONS AND MEANS FOR GROUPING THE SAME.

Application filed April 22, 1924. Serial No. 708,306.

To all whom it may concern:

Be it known that we, NATHAN SPARER, a subject of the Government of Austria, and a resident of Somerville, in the county of Middlesex and Commonwealth of Massachusetts, and MAX HALPERSON, a citizen of the United States, and a resident of Boston, in the county of Suffolk and Commonwealth of Massachusetts, have invented certain new and useful Improvements in Buttons and Means for Grouping the Same, of which the following is a specification.

This invention relates to buttons and more particularly to ornamental or trimming buttons such as might be used in the decoration of ladies' garments or millinery.

It is an object of the invention to produce a covered button, preferably of ornamental character but not necessarily so, which is adapted to be secured to a garment or other article singly, or in group with others of different contour and design, or which may be secured, in a line side by side with others of the same or different contour or design, by means of a common carrier such as cord, wire or tape.

A further object of the invention is to produce a covered button which may be arranged as above by simple and inexpensive means, said arrangement not being dependent upon a step, in, or process of manufacture of the button, but may be accomplished at any time after the assembly of the button, and by so doing the use of special and expensive dies is eliminated and a great variety of sizes and shapes of buttons may be grouped or strung together, with greater speed and much less expense, than is possible with buttons of this class that are at present in use.

A still further object of the invention is the production of a covered button, which, during the process of manufacture, has provision made therein to secure it in one of two ways to a garment or other object, first by using the said provided means to directly secure it to a garment, second, to use the said means to secure it to a carrier or connector common to a plurality of buttons, which may later be secured to a garment to form a design thereon if desired, or since

the button in the present instance has a covered back, the usual method of stitching it on may be resorted to.

In the first instance, the means referred to, may be made to directly engage the material of the garment, or other article, and upset to clinch the material, in the second instance the connector, comprising either tape or cords, is directed into fastening position with the said means and the said means upset to clamp the connector. 55 60

It is known that covered buttons have, heretofore been strung on a connector, but in the instance in mind, the stringing was done when the front and back parts of the button were being assembled, and therefore only one style and size of button as well as shape, could be commercially strung on the same connector, thus limiting the possibilities of design of a string to a single size and shaped button. 65 70

The present invention contemplates a covered button which may be applied to a garment, for instance, as an individual, or it may be strung with others of a different size and shape on a connector which in turn may be secured to a garment, or made to form a belt. 75

The invention also contemplates the method of stringing the buttons, which method enables an operator to string them with speed and accuracy regardless of size or shape and by the use of simple means. 80

The invention further consists in certain features which will be fully understood from a description of the drawings and the claims hereinafter given. 85

Of the drawings:

Figure 1 represents in face view a plurality of covered buttons of different sizes and shapes secured to a connector which in the present instance consists of two cords or wires. 90

Figure 2 is a rear view of Figure 1. 95

Figure 3 is a section, enlarged on the line 3—3 Figure 1 showing the button prior to be secured to the connector.

Figure 4 is a view similar to Figure 3 but showing the button secured to the connector. 100

Figure 5 is a top plan diagrammatic view of

the means to aid in stringing the buttons on the connector.

Figure 6 is a section through one form of adjustable rest for the button, in which it is held while being secured to the connector.

Figure 7 is a view of a button showing the securing means thereon and the plunger for upsetting said means.

10 Figure 8 is a detail to be referred to.

Like characters designate like parts throughout the several figures of the drawing.

Referring to the drawing:

15 The drawing herewith illustrates a plurality of buttons 10, 11, 12 and 13, of different sizes and shapes, as strung with others to form a design or ornamentation such as might be used for dress trimming or as a 20 belt for ladies' wear.

It is an object of the present invention to produce a button which may be readily strung as shown in the drawing, or which may be secured to a garment singly, or in 25 group, and which may be strung on a cord or tape at any time after the assembly of the button, in a rapid and accurate manner.

To the attainment of the objects of the invention, the button such as 13, herein 30 shown as a plaited button somewhat similar to that described and claimed in Patent No. 1,486,309, granted March 13, 1924, is in, the present instance composed of a front portion 14, and a back portion 15 assembled 35 as seen in Figures 3 and 4 of the drawing herewith.

The front portion comprising a shell 16, an ornamental plaited face 17, and tie member 18 therefore, is or may be as shown in 40 said patent.

The back portion however is slightly different in make-up, being in the present instance composed of a shell 19 having a cover of fabric or other suitable material 45 20; the said shell 19 being provided with ears or spurs 21, struck up from the material of the shell and adapted to pierce the cover 20 before being bent toward each other as seen in Figure 3 of the drawing.

50 At any time after the front and back portions have been assembled and while the button is in the condition shown in Figure 3, it may be assembled with others as shown in Figure 1, or it may be attached to a dress or garment by inserting the spurs 21 thereinto and clinching them, or it may be sewed on by stitching through the material 20 in the usual manner.

When it is to be assembled with others, 60 it is placed in an adjustable holder 22 such as shown in Figure 6, with its back portion uppermost, and cords 23 positioned under the overhanging spurs 21 as seen in Figure 5, and a plunger 24 allowed to descend to

70 clinch the spurs around the cords to thus 65 secure the button in place.

The cords 23 are preferably lead from spools 25 which are under the tension of springs 26, said spools being separated a sufficient distance apart to ensure their retention in place under the spurs during the operation of upsetting, as clearly shown in 75 said Figure 5 of the drawing.

The particular structure of the adjustable holder is of no great importance so long as it is adaptable to different sizes and shaped buttons, and in view of that fact, it is not thought advisable to enter into a detailed explanation thereof.

It is not known that an ornamental, covered button has ever been made that could be directly secured to a garment wholly by means forming part of the button, or that could be secured by the same means to a connector common to other buttons or devices and through that means secured to a garment, or that in lieu of the use of the aforesaid methods, could be sewed on in the usual way.

It will be understood that in the place 90 of cord as a connector, tape might be used as shown in Figure 8 of the drawing, and therefore it is not the intention to limit the invention to the precise construction shown as it is possible to make changes therein 95 without departing from its spirit and scope.

Having described the invention we claim:

1. A covered button adapted for decorative purposes having front and back portions assembled to form said button, both 100 of said portions having covers; and spurs forming part of and projecting from said back portion and piercing the cover thereof whereby said button may be attached to an article by said spurs.

2. A button comprising a plurality of parts one of which has spurs forming part of and projecting therefrom and piercing another of said parts, said spurs being adapted to secure said button to a connector; 110 in combination with a connector adapted to receive a plurality of said buttons.

3. A button having a front portion and a covered back portion said cover of said back portion being of a material adapted 115 to receive stitches whereby said button may be attached to an article; and means forming part of said back portion and protruding through said material and adapted to secure said button to an article independently of said back portion cover.

4. A button comprising a front portion of stiff material; a cover for said front portion; a back portion of metal; a cover of fabric for said back portion; and spurs struck up from said metal back portion and piercing said back portion cover whereby said button may be attached to an article,

5. A button having means forming part thereof to secure it to a connector; a connector; and means to string said button on said connector and comprising a holder for said button, means to convergently present two cords to said holder and means to cause said button to become secured to said connector while said button is in said holder; and means to adjust said holder to accommodate various sizes of buttons. 10
Signed by us at Boston, Massachusetts, this 21st day of April, 1924.

NATHAN SPARER.
MAX HALPERSON.
